UNITED STATES PATENT OFFICE.

JOSEPH A. MANAHAN, OF NEW YORK, N. Y., ASSIGNOR TO THOMAS MANAHAN, OF NEW YORK, N. Y.

CHAIR.

SPECIFICATION forming part of Letters Patent No. 733,857, dated July 14, 1903.

Application filed December 22, 1902. Serial No. 136,237. (No model.)

To all whom it may concern:

Be it known that I, JOSEPH A. MANAHAN, a citizen of the United States, residing in Manhattan borough, New York city, in the county 5 and State of New York, have invented new and useful Improvements in Chairs, of which the following is a specification.

This invention relates to certain improvements in chairs having adjustable backs; and 10 the invention resides in the novel features of construction set forth in the following specification and claim and illustrated in the annexed drawings, in which—

Figure 1 is a detail view of a lever. Fig. 2 15 shows a face and an edge view of the bracket forming a fulcrum for the lever. Fig. 3 shows a spring. Fig. 4 shows a face and an edge view of the guide-bracket for the lever. Fig. 5 shows a perspective and an end view of the 20 spring for holding the lever in locking position. Fig. 6 shows a chair embodying this invention.

In the drawings the chair is shown having a movable or hinged back O. A regulating- 25 lever A is hinged or fulcrumed to the back and has its free end extended forward under the arm P of the chair. A guide-bracket K for the lever is secured to the arm P. The lever has a rack portion B at its lower edge, 30 and the pin L in bracket K forms a tooth or catch portion to coact with the lever-teeth. The spring M at the chair-arm acts on the lever to press its rack portion to engagement or to lock with the lever guide-bracket K or 35 its cross-pin L. The fulcrum of the lever is formed by a bracket F, having screw-holes H for connection with the chair-back, and a reduced or shouldered pivot portion G, with an eye I. The lever being pushed onto pivot or 40 fulcrum G up to the shoulder formed by body part F, the spring J is hooked or connected

to the eye or end portion I. Said spring being also connected to guide-bracket K, the tension of said spring tends to raise the chair-back to normal position or toward the vertical. By raising the lever against the pressure of spring M the lever-rack B is unlocked or freed from lock L, and the back can then be forced back against the tension of the lifting-spring J to the desired inclination. The 45 lever being then freed, the spring M presses the lever downward to engage or lock with the bracket and hold the back in position.

The lever A is suitably enlarged, as seen at C, to allow for the formation of rack B, and 50 the lever part D has the eye E to slip onto fulcrum-pin G. The spring M has its end N suitably shaped and grooved to sit on or straddle the lever A and remain in engagement therewith. The spring J when hooked 55 into eye I holds the lever in place, so that it will not slip off the fulcrum.

What I claim as new, and desire to secure by Letters Patent, is—

A chair having a movable back, a shoul- 65 dered and perforated bracket secured to the back, a lever slipped onto the bracket to sit against the shoulder, a spring hooked into the eye of the bracket to hold the lever in place, a guide-bracket to which the spring is 70 secured to lift or move the back to vertical position, and a lever guided by the guide-bracket and having teeth adapted to lock to said bracket.

In testimony whereof I have hereunto set 75 my hand in the presence of two subscribing witnesses.

JOSEPH A. MANAHAN.
